[57] CLAIM

The ornamental design for a dispensing applicator, as shown and described.

DESCRIPTION

FIG. 1 is a top plan view of the dispensing applicator embodying my new design;

FIG. 2 is a front elevational view thereof;

FIG. 3 is a left end elevational view thereof;

FIG. 4 is a right end elevational view thereof;

FIG. 5 is a bottom plan view thereof;
FIG. 6 is a vertical section taken along lines 6—6 of FIG. 1.

The rear elevational view, now shown, is the mirror image of the front elevational view shown in FIG. 2.

Fig. 1

Fig. 2
